SMOKER'S ASH TRAY OR SIMILAR ARTICLE

Burrell T. McNair, Dallas, Tex.

Application July 8, 1949, Serial No. 3,787

Term of patent 14 years

(Cl. D85—2)

To all whom it may concern:

Be it known that I, Burrell T. McNair, a citizen of the United States, residing at Dallas, in the county of Dallas and State of Texas, have invented a new, original, and ornamental Design for a Smoker's Ash Tray or Similar Article, of which the following is a specification, reference being had to the accompanying drawing, forming part thereof.

Figure 5 is a rear end elevational view of a smoker's ash tray or similar article showing my new design.

I claim:

The ornamental design for a smoker's ash tray or similar article, substantially as shown.

BURRELL T. McNAIR.
